UNITED STATES PATENT OFFICE

2,587,637

DETERGENT COMPOSITION

Louis McDonald, Inyokern, Calif.

No Drawing. Application December 18, 1947,
Serial No. 792,617

4 Claims. (Cl. 252—130)

1

The present invention relates to detergent compositions and it particularly relates to detergent compositions which may be used as such in cake, powder, flake or liquid form on which may be impregnated upon or mixed with various fibrous, porous or abrasive materials which may serve as carriers therefor.

It is among the objects of the present invention to provide a detergent material of low solvent properties which may be readily incorporated with fibrous, abrasive and filler materials and which will not too quickly dissolve or melt away when utilized with hot or cold soft waters and which will be effective over long periods of time with undiminished detergent efficiency.

Another object of the present invention is to provide novel detergent compositions which may be incorporated with paper fibers or toweling, steel wool, various abrasives such as emery and sand and which will not tend to dissolve away too quickly from the material with which they are incorporated or by which they are carried before they have had the opportunity of being effectively used for their detergent properties.

Another object of the present invention is to provide novel detergent materials which may be readily employed either in the home or industrially and which will retain their effectiveness over long periods of time and which will have high detergent properties even with salt water or with waters having widely varying degrees of temporary or permanent hardness or having varying temperatures.

Still further objects and advantages will appear from the more detailed description set forth below, it being understood, however, that this more detailed description is given by way of illustration and explanation only, and not by way of limitation, since various changes therein may be made by those skilled in the art without departing from the scope and spirit of the present invention.

In accomplishing the above objects, it has been found most satisfactory to combine either alone or in combination with fatty acid soaps with an ordinary fatty acid soap a water insoluble material which will slow up and retard the dissolution of the actual active detergent ingredient.

Although the fatty soap may be sodium, ammonium or potassium oleate, stearate, laurate, or palmitate or the various mono, di, or tri-ethanolamine oleates, stearates and palmitates, it has also been found possible to employ various sodium, ammonium or potassium salts of sulphonated or sulfated fatty alcohols, fatty ketones, fatty acids

2

and hydrocarbons having from 12 to 32 carbon atoms.

With this combination is preferably combined a water insoluble, plastic material, cellulose ethers, particularly ethyl cellulose, being preferred. Propyl, butyl and amyl celluloses may also be employed as may also benzyl cellulose in lieu of part or all of the ethyl cellulose.

It has also been found quite satisfactory to include in such compositions small amounts of an inorganic crystalloid detergent salt such as sodium carbonate, sodium phosphate or sodium hexametaphosphate.

In the preferred composition it is also desirable to include water thickening agents or protective colloids such as various gums, like gum acacia, gum tragacanth, gum arabic, agar agar, pectin, dextrin, British gum, gum Shiraz or water soluble cellulose derivatives, such as methyl celluloses. Methyl celluloses in contrast to ethyl cellulose are usually water soluble. The preferred methyl cellulose has a solubility of 64 grams per 100 ml. at 25° C. with 2.6 methoxy groups per 12 carbon cellulose unit.

These compositions may be mixed with fillers and/or abrasives, such as powdered sand, infusorial earth, kieselguhr, whiting, or it may be impregnated upon cloth, paper or other fibrous materials, or upon aluminum, steel or other metal wools or upon glass rock, or mineral wool or upon fibrous mattings, such as those made from hemp or artificial fibers.

With the detergent compositions of the present application, it is important that the detergent base have self-emulsifying ethyl cellulose binders which retard the dissolution or emulsification of the detergent material from the filler or carrier material with which it has been incorporated or onto which it has been impregnated, and where desired, the final composition may be caused to incorporate substantial quantities of air which will cause it to be a floating soap which when floated upon water will not readily emulsify or dissolve.

Commercial ethyl cellulose is normally water insoluble and can only be dispersed in water by way of an emulsion. Such dispersion may be made in the following manner: The ethyl cellulose, for example 50 parts by weight of ethyl cellulose having 2.5 ethoxy groups per glucose residue, is first dissolved in toluene ethanol mixture (40 parts toluene—60 parts ethanol by weight) and then this organic solvent solution is dispersed in a water solution of 2 to 3 parts of manitan mono-oleate in 97 to 98 parts of water.

These are mixed in a high speed mixer or colloid mill and then after initial emulsification they are homogenized. The final product is a heavy creamy emulsion containing about 25% ethyl cellulose.

Commercial methyl cellulose containing 2.5 methoxy groups per glucose residue is water soluble and is used as an emulsion stabilizer, as a sizing gum and if mixed with soap or a detergent would not act in any respect as ethyl cellulose. It is used for example in shaving creams to stabilize lather.

For example whereas ethyl cellulose promotes micelle formation a micelle being a bundle of detergent or soap molecules, methyl cellulose if used in the same quantities as the ethyl cellulose would have no such effect.

Ethyl cellulose slows rate of solution of soap by 50% to 300% depending upon proportionment. Methyl cellulose does not have this effect.

Methyl cellulose may be mixed with soap up to 40% directly without substantially decreasing insolubility of the soap. But ethyl cellulose can only be incorporated up to about 2% above which it would render soap virtually insoluble.

It has been found desirable to include in the composition, in lieu of all or part of the polyethylene glycol esters, small amounts from 1 to 50% by weight of highly effective surface active agents, such as, for example, normal polymerized dialkyl sulphonates, such as of the nature of dibutyl naphthalene sodium sulphonates, or of alkyl esters of di-basic carboxylic acids, such as the dioctyl ester of sulfosuccinic acid, or sodium fatty alcohol sulfates such as sodium lauryl sulfates.

These materials should preferably be of anionic or non-ionic nature. Cationic agents are less preferable for most applications but may be advantageously used for low pH types of soils.

Among the other surface active materials which may be used are Triton 770, Triton NE, Arctic Syntex M, Igepal CA, Igepon T or other collamids, Tween 20 and Tween 60.

The collamids are generally of the formula:

where R is an alkyl group of 12 to 22 carbon atoms, Igepon T being a typical commercial example and having as the alkyl group C₁₇ H₃₃.

Triton 770 is a polysulphonate of an aromatic polyalkylene ether sulfate having the general formula:

Arctic Syntex M has the general formula:

Triton NE and Igepal CA are the same products and consist of polyethylene oxide condensates having $(-\text{C}-\text{C}-\text{O}-\text{C}-\text{C})_n\text{OH}$ groupings with molecular weights of 750 to 1000. Triton NE has the following formula:

where n is 8 to 90 ethylene oxide groups. The commercially available material contains approximately 12 ethylene oxide groups.

Igepal CA is identified by the formula:

where n represents 1 to 20 ethylene oxide groups. The commercial material contains about 6 ethylene oxide groups.

Tween 60 is sorbitan monostearate, while

Tween 20 is sorbitan laurate. The Triton 770, Triton NE, Arctic Syntex M, Tween 20 and Tween 60 may all be included by the term "aliphatic organic non-cationic type non-soap detergent or surface active agent."

To give several examples of various detergent compositions according to the present application all parts being by weight:

EXAMPLE I

A metal cleaning detergent composition which may be impregnated on cloth, paper or other fibrous materials such as aluminum wool, steel wool, rock wool, or fibrous mattings made of hemp, or artificial fibers, may be made up in the following manner:

As batch A, the following composition is prepared with gentle mixing at a temperature of about 40° C.:

	Preferred	Range
Ethyl cellulose	2	1-4
Methyl Cyclohexanone glyceryl acetal hereinafter called Cyclonol	2	0-4
25 Ethylene glycol monobutylether	10	5-25
Castor oil	4	0-10
Dibutyl phthalate	1	0-2

Prepare batch B from the following ingredients, with stirring and gentle heating at 40° C.:

	Preferred	Range
35 Oleic acid	20	5-30
Monethanolamine	7	2-10
Ammonium gluconate	5	0-10
Sodium hexametaphosphate	10	0-20
Diethanolamine	10	2-15
Whiting (finest bolted)	75	50-150
Infusorial earth (#200)	50	25-100
Methyl cellulose ether	4	0-50
Isopropyl alcohol	25	0-50
40 Dibutyl naphthalene sodium sulfonate	35	0-50
Water	300	150-600

After each of batch A and batch B has been thoroughly mixed they are separately warmed to 45 70° C. and then batch A is poured into batch B with rapid agitation, emulsification taking place immediately.

Then the mass is agitated until it cools to 50° C. and it is transferred to a colloidal mill and homogenized.

The resultant emulsion may be impregnated upon paper or cloth or other fibrous materials, and the impregnated product may be dried under a vacuum or by gentle heating. The finished 55 product may be used for cleaning metals by dampening the impregnated material with warm water and rubbing on the tarnished metal object until all tarnish is removed.

It will be noted that the composition only dissolves slowly with hot water and does not melt too readily.

In the composition set forth above, other oils may be utilized in lieu of castor oil and other alkalies or alkaline materials may be used in lieu 65 of the ethanolamines specified.

Dibutyl phthalate is merely a plasticizer and may be replaced by other plasticizers and in lieu of oleic acid, it is possible to use other fatty acids to combine with the alkali present.

70 In lieu of the ethyl cellulose utilized, other water insoluble cellulose ether derivatives may be employed as binders to slow up solution of the fatty acid soap compound which is formed.

In lieu of the infusorial earth, other abrasives 75 or fillers may be employed.

EXAMPLE II

Another metal cleaning composition may be made up for impregnation upon paper, cloth or steel wool in the following manner:

First batch A is made up, consisting of the following ingredients (all parts being by weight):

	Preferred	Range
Ammonium stearate.....	30	10-50
Mineral oil.....	10	2-25

Then batch B is made up, consisting of the following ingredients:

	Preferred	Range
Triethanol amine.....	10	2-15
Infusorial earth.....	50	25-75
Tricalcium phosphate.....	100	50-150
Ethyl cellulose.....	3	1/4-6
Diethyl ester of sodium sulfosuccinic acid.....	30	10-45
Isothymol.....	0.5	0-1
Water.....	400	150-600
Sodium hexametaphosphate.....	20	5-40

The ingredients of batch B are first mixed in the water at about 30°, while the chemicals of batch A are mixed at about 70° C. and poured into batch B with rapid agitation, which agitation is continued until the emulsion cools to 20° C.

The emulsion is then transferred to a colloid mill and homogenized and then used as a detergent as such with or without the addition of filler, or it may be impregnated upon paper, cloth, or steel or metal wool and then dried in a vacuum or by gentle heating.

In the composition stated, the ethyl cellulose acts as a binder.

The sodium hexametaphosphate will act as a cleansing agent.

EXAMPLE III

To obtain a floating soap composition, $\frac{5}{10}$ gram of benzyl cellulose having 25 benzyloxy groups per glucose residue may be emulsified with grams of diglycol oleate and then to the emulsion there may be added 90 grams of hard soap and $7\frac{1}{2}$ grams of sodium laurylsulfonate.

The entire mass is heated to about 100° C. and is transferred to a "paste mixer," soap remelter or crutcher.

While the mass is being kneaded in the mixer, 5 grams of water is added. The mass is then agitated very rapidly and is then removed to a vacuum oven or soap frames for drying. While drying the mass can be molded into cake form. The finished cake is a "floating" detergent which will not rapidly dissolve while floating on water.

When the cake is rubbed it will, however, re-emulsify and produce a heavy lather.

The detergent functions satisfactorily in hard water and the formation of calcium and magnesium soap curd is repressed by the diglycol oleate and the sodium lauryl sulfonate or sulfate. This detergent cake is not sensitive to the changes in atmospheric conditions. It does not lose weight in warm, dry weather, nor does it absorb moisture and become soggy in humid weather.

EXAMPLE IV

To make detergent materials which will be effective in hard water or water containing calcium or magnesium salts, the following composition may be made:

One gram of polyvinyl alcohol is emulsified

with 5 grams of mannide monooleate. To this mixture is added 90 grams of kettle soap and the entire mass is transferred to a "paste mill." The temperature is brought up to 100° C. and the mass is kneaded.

Kettle soap is 65% soap and the balance water and glycerin.

After a mass of even consistency is attained, 2 grams of tetrasodium pyrophosphate dissolved in 8 cc. of hot water are added and mixing is continued. The mass is then transferred to a vacuum oven and dried and molded into cake form or to soap frames and cooled or molded into cake form. The finished cake is smooth and has the appearance of conventional soap.

This detergent may be used in hard water with complete satisfaction. This composition enables incorporation of a crystalline electrolyte water softening agent which was not previously possible with soap compositions. Instead of polyvinyl alcohol, dimethylol urea having more than 4 mole units per molecules, diomeric or triomeric methacrylates, and diomeric or triomeric vinylidene chlorides or acetates may be used. These are all water insoluble and organic solvent soluble resins.

EXAMPLE V

To make a detergent composition which may be conveniently impregnated onto crepe paper 20 toweling or formed into a film detergent which then may be used for washing the face, hands or various inanimate objects, the following composition may be made:

One gram of ethyl cellulose is emulsified with 23 two grams of mannitan monooleate.

The mass is mixed in a "paste mill" and 97 grams of hard soap and 5 grams of secondary octyl alcohol sulfate or secondary cetyl alcohol sulfate is added.

The temperature is brought up to 70° C. and the entire mass is agitated until a smooth paste is obtained. The mixture is transferred to a colloid mill and homogenized with 500 cc. of water at 70° C. The resulting emulsion is transferred to a tank and is impregnated onto paper toweling in the conventional manner. The product is dried in a vacuum drier or by gentle heating. The impregnated paper is stable under various climatic conditions and may be rolled or packaged in cut form.

The product may be cast or rolled into a film without fibrous backing.

The paper towelling made with this composition may be dispensed with ordinary dispensing machines in public wash rooms and may be used to eliminate the inconvenience of liquid, powdered and cake soaps in public wash rooms.

As the towel is rubbed on the wetted object, the detergent will re-emulsify and cleanse the object with the above composition.

EXAMPLE VI

A bead soap product that is stable in all climatic conditions and that will not become soggy can be made as follows:

$\frac{5}{10}$ gram of ethyl cellulose is emulsified and plasticized with 2 grams of glycerylmonostearate. To this mass is added a mixture of 92.5 grams of kettle soap and 5 grams of sodium myristyl collamide. The entire mass is kneaded in a "paste mill" or a crutcher and when thoroughly kneaded it is blown into beads in the conventional manner.

This detergent product also functions effectively in hard water. A flake or powdered deter-

gent composition can be made from the same formula. The kneaded mass is dried and run through a "flaker" and the product is then ready for distribution.

It has been found that the detergent compositions described above may be impregnated onto paper or other fibrous material in the process of manufacture of such material.

For example, in making a crepe or tissue paper, the detergent chemicals can be mixed in the beater along with the pulp and binding materials, and will not be removed with the wash water.

The use of a self-emulsifying plasticizer for a cellulose ether substance permits the detergent materials to be incorporated into the fiber in the process of manufacture.

EXAMPLE VII

A tissue paper which may be used for cleaning silver and other fine metals may be made as follows:

A beater mass is made up with twenty pounds of sulfite pulp dispersed with 400 lbs. of water. While the pulp is agitating in the beater, 10 pounds of detergent emulsion is made up in Example I or II.

After the entire mass is thoroughly mixed, it is run out on the screen and from there through the rollers of a paper making machine in the conventional manner.

The drip liquid from the screen can be recovered and used again in the beater.

It is possible to use the above detergent compositions for cleaning metal. In compositions for cleaning metals such as aluminum, gold, silver, tin, brass, copper, nickel, etc. which are impregnated on metal wools or abrasives or paper or cloth carriers and rubbed on the utensil or other metal object that is being cleaned the composition may desirably include a polyhydroxy organic acid, lactone or polyhydroxy organic salt suspended in an emulsified binder with a polishing agent and wetting agent.

The polyhydroxy organic acids and lactones such as gluconic acid and gluconodeltalactone are preferred.

The mixture may be impregnated into a carrier such as canton flannel or similar textile material, crepe paper toweling or tissue paper, or a suitable metal wool such as aluminum wool or a fibrous or wool siliceous mass such as mineral wool and rock wool. The cleaner composition and the fibrous wool carrier or abrasive may be modified for the cleansing and polishing of different metals, and all the agents used should be non-toxic and non-irritating to the skin.

It is usually desirable to include agents which act as emollients and prevent the skin from drying or chafing when the composition is used.

EXAMPLE VIII

A composition suitable for cleaning silver, gold or platinum impregnated into canton flannel or similar textile material is made up in two batches of the following ingredients:

Batch A

Paraffin oil (light)	15
Diglycol laurate	30
Diglycol stearate	10
Diethylene glycol-monobutyl-ether acetate	10
Ethyl cellulose	5
Beeswax	5
Cyclonol	5
Dibutyl phthalate	5

Batch B

Water	300
Isopropyl alcohol	75
Methyl cellulose	4
Sorbitol	20
Infusorial earth (200 mesh)	75
Keryl C ₂₀ to C ₂₆ or cetyl benzene sodium sulfonate (100%)	50
Glucconodeltalactone	50

Batches A and B are both mixed while heating to 70° C.

Then batch B is poured into batch A with rapid stirring.

Emulsification takes place immediately and the mass is stirred rapidly until the temperature drops to 50° C. The mixture is then run through a homogenizer to complete emulsification.

The temperature is then adjusted to 35° to 40° C. and the emulsion is transferred to a tank.

A ribbon of canton flannel or similar textile is run through the emulsion and the fibres of the textile become impregnated. The excess emulsion is scraped off the bottom of the cloth and the wet impregnated mass is run through a vacuum dryer or is dried by gentle heating.

The finished impregnated cloth may be used for cleaning silver by moistening the cloth with a small amount of warm water and then rubbing on the tarnished silver. The impregnated chemicals re-emulsify and are liberated from the cloth to act on the soil and tarnish. After the tarnish is removed the silver is rinsed with warm water and is ready for use.

EXAMPLE IX

A similar cleansing composition may be made by impregnating crepe of tissue or other soft paper with an emulsion formed of the following ingredients:

Batch A

Paraffin oil (light)	15
Ethyl cellulose	5
Beeswax	5
Diglycol laurate	30
Diglycol stearate	40
Diethylene glycol-monobutyl ether acetate	5
Cyclonol	4
Dibutyl phthalate	1

Batch B

Water	900
Isopropyl alcohol	25
Methyl cellulose	4
Sorbitol	20
Infusorial earth (200 mesh)	100
Phenyl sulfonate ethylene oxide alcohol sulfate (100%)	50
Glucconodeltalactone	50

The emulsion is made in the same manner as in Example VIII and the paper is impregnated in the same manner as was the cloth.

The dried impregnated paper may be cut into rolled strips and dispensed in much the same manner as rolled paper towels. The impregnated cleaning paper is torn off from the roll and used as needed. The paper is moistened with warm and rubbed on a tarnished silver article until it is cleaned. Then the soiled paper may be discarded.

EXAMPLE X

For cleaning base metals such as aluminum, zinc, copper, steel, tin, nickel, etc. the following composition may be used:

Batch A

Petrolatum	10
Ethyl cellulose	7
Beeswax	5
Diglycol laurate	30
Diglycol stearate	20
Diethylene glycol-monobutyl ether acetate	5
Cyclonol	6
Dibutyl phthalate	1
Isothymol	0.5

Batch B

Water	300
Isopropyl alcohol	25
Methyl cellulose	5
Sorbitol	20
Infusorial earth (200 mesh)	30
Polyethylene oxide alcohol—20 to 90 C ₂ H ₄ O groups (100%)	50
Gluconic acid (50%)	100
Tri-isopropanol amine	3

An emulsion is made in the same manner as in Example IX. Then the emulsion is impregnated into a porous or abrasive mass such as aluminum wool, copper wool, mineral wool or rock wool. Also, the emulsion may be impregnated into a woven pad made of ordinary cotton fiber and soft metal fibre. Metal fibers such as copper and aluminum are suitable for this purpose. Strips of woven metal cloth woven from aluminum, copper or other soft-non-corrosive metal wire may be used.

In the above compositions the cyclonol or cyclo hexanone glycerol acetal and the diethylene glycol-monobutyl ether acetate act as high boiling solvents which keep the emulsion at impregnating consistency and also act to plasticize the binder.

The cyclonol also acts as a grease solvent.

Cyclonol also acts as a true non-emulsifying plasticizer for the ethyl cellulose.

The isothymol acts as a preservative.

The isopropyl alcohol acts as a solvent for the ethyl cellulose while the sorbitol acts as a humectant and controls the moisture content.

The gluconic acid combines with the tri-isopropanol amine to form a salt in part, the remainder being free acid.

The above compositions are typical but merely illustrative of the scope of this invention. The proportions of the chemicals used may vary considerably from the amounts cited above without departing from the spirit of this invention. Certain chemical agents may be substituted for those cited above.

For example, arabic, arabonic, xylonic, saccharonic or tri-hydroxy glutaric acids may be substituted for gluconic acid.

Any suitable abrasive material such as bentonite, tripoli or rottenstone may be substituted for infusorial earth. Other emulsification bases than diglycol laurate and diglycol stearate may be used. Such emulsification bases are mannide monooleate, manitan monooleate, diglycol oleate or diethanolamine stearate.

There are many wetting agents that may be used in place of the cited alkyl aryl-sulfonates.

A few of the preferred ones are sodium dibutyl naphthalene sulfonate, sodium lauryl alcohol sulfate, sodium tetrahydronaphthalene sulfonate, the sodium sulfonate of stearyl alcohol, sodium lauryl sulfate and sodium salt of sulfonated myristyl collamide.

Protective colloids other than methyl cellulose

may be used. Such gums as locust bean gum, gum tragacanth, India gum or gum arabic are useful. Such gums also may be replaced by water soluble protein materials such as albumin, gelatin or casein.

Resin binders such as low polymerized vinyl acetate, or polyvinyl alcohols may be substituted for part or all of the ethyl cellulose, if tackiness is avoided.

The present invention is particularly advantageous where it is desired to have a relatively slow dissolving soap as in the case of floating or aerated soaps which tend to dissolve too quickly in water, or where the detergent is combined with a fibrous or abrasive material and tends to dissolve away from the fibrous material or abrasive too quickly before such fibrous material or abrasive can be thoroughly rubbed upon the object being cleansed. Moreover, the detergent compositions according to the present application are more resistant to atmospheric changes and will not lose weight or gain water with changes from temperate to tropical climates, or with varying humidity or temperature changes in the same locality. The soaps according to the present application may be kept in wet dishes or containers without unduly softening, wasting away or becoming mushy, and where the soap is used in the form of beads, flakes or a powder, there will be decreased tendency toward caking or hardening.

Moreover, the water solubility retarding agent tends to protect the detergent from oxidation.

Where desired, it is possible to employ the slow dissolving soaps of the present invention in combination with ordinary, relatively quick dissolving soaps or detergents with the soap or detergent of the present invention constituting an outer layer or a protective surfacing or being

mixed with the entire body of the ordinary detergent or soap so that there will be pockets or layers of ordinary detergents or soap which will quickly dissolve when exposed while other layers or pockets of slow dissolving soap, as according to the present invention, will only slowly dissolve.

Among the detergents that may be employed are cleaners for metals such as glucono-lactone, ammonium gluconate, trihydroxy glutaric acid, sodium hexametaphosphate, sodium metasilicate; toilet detergents such as sodium, potassium or alkanolamine stearates, oleates, laurates, palmitates and myristates; fatty alcohol detergents, such as sodium lauryl or palmityl or oleyl sulphate, sulphonated fats, oils or fatty acids or alcohols such as sulfonated castor oil, tea seed oil, olive oil, peanut oil, cottonseed oil, spermaceti, cetyl alcohol, japan wax, fish oils, lard, rice bran oil, and so forth; the sodium salts of sulphonated or sulphated esterified dicarboxylic acids and so forth. The detergent may constitute from 5 to 80% of the composition.

The soap and non-soap detergents themselves are not emulsifying agents for the ethyl cellulose or resinous or plastic solubility retarding material and it is necessary to add a material which will emulsify the ethyl cellulose or other solubility retarding material.

The ethyl cellulose or other solubility retarding materials may range from 0.1 to 5% by weight, while the emulsifying agents, usually oil active surface agents such as partially fatty acid esterified polyhydric aliphatic alcohols for the solubility retarding materials may range from 0.005% to 2%.

The water soluble, organic solvent soluble,

resinous solubility retarding agents, such as glycerol modified urea formaldehyde, methacrylate, vinyl acetate, vinylidene chloride, styrene, and similar resins may be plasticized and emulsified by a substance such as diglycol laurate, mannide oleate or laurate, mannan oleate, diglycol stearate, glycerol mono-stearate, diglycol oleate, or partly fatty acid esterified sorbitol, mannitol or ducitol, and so forth. These last mentioned plasticizers are also self-emulsifying in water preventing the solubility retarding agent from caking, precipitating or separating out when the detergent is being used.

Mannide oleate or mannan oleate permit incorporation of water softening agents, such as tetra sodium pyrophosphate, sodium hexametaphosphate and so forth without these substances crystallizing in the composition. These self-emulsifying plasticizers are usually polyhydric alcohols, one or more of the hydroxy groups of which are combined with high molecular weight fatty acids with one or more free hydroxy groups.

Oils, waxes and fats are added as lubricants and may be used in amounts from $\frac{1}{2}$ to 10%.

Where water soluble or dispersible gums, such as methyl cellulose, India gum and dextrin are employed they may be used in amounts ranging from $\frac{1}{2}$ to 5%.

Where organic solvents such as isopropanol, ethylene glycol alkyl ethers, and so forth are employed they are evaporated off and reclaimed.

The present application is a continuation-in-part of application Ser. No. 405,659, filed August 6, 1941, and now abandoned.

Many other changes could be effected in the particular features of detergent compositions described, and in methods of usage set forth, and in specific details thereof, without substantially departing from the invention intended to be defined in the claims, the specific description therein merely serving to illustrate certain elements by which, in one embodiment, the spirit of the invention may be effectuated.

What is claimed is:

1. A solid detergent composition formed of a sodium soap of high molecular weight fatty acid and about 0.1% to 5% by weight of a water-insoluble ethyl cellulose to retard ready solution of said soap and from about 0.005% to 2% of a partial high molecular weight fatty acid ester of a polyhydric aliphatic alcohol.

2. A solid detergent composition formed of a sodium soap of high molecular weight fatty acid and about 0.1% to 5% by weight of a water-insoluble ethyl cellulose to retard ready solution

of said soap and from about 0.005% to 2% of a partial high molecular weight fatty acid ester of a polyhydric aliphatic alcohol, the emulsifying agent being mannan monoleate.

3. A solid detergent composition formed of a sodium soap of high molecular weight fatty acid and about 0.1% to 5% by weight of a water-insoluble ethyl cellulose to retard ready solution of said soap and from about 0.005% to 2% of a partial high molecular weight fatty acid ester of a polyhydric aliphatic alcohol, the ethyl cellulose containing about 2.5 ethoxy groups per glucose residue.

4. A solid detergent composition formed of a sodium soap of a high molecular weight fatty acid and about 0.1% to 5% by weight of a water-insoluble ethyl cellulose to retard ready solution of said soap and an emulsifying agent consisting of a partial high molecular weight fatty acid ester of a polyhydric aliphatic alcohol in an amount sufficient to emulsify said ethyl cellulose into the soap.
